UNITED STATES PATENT OFFICE.

JAMES T. DOWDALL, OF GLEN MORRIS, NEW YORK.

SEWING-MACHINE ATTACHMENT FOR SEWING SWEATBANDS TO HATS.

Application filed November 23, 1923. Serial No. 676,500.

To all whom it may concern:

Be it known that I, JAMES T. DOWDALL, a citizen of the United States of America, residing at Glen Morris, Queens County, State 5 of New York, have invented certain new and useful Improvements in Sewing-Machine Attachments for Sewing Sweatbands to Hats, of which the following is a specification.

10 This invention relates to sewing machine attachments for sewing sweat bands into hats and in particular to an attachment whereby the band may be applied to a hat through the medium of an intermediate 15 member rather than being applied directly to the hat as is the present practice.

A particular object of my invention is to provide a means for fastening a sweat band in place which will eliminate an undesirable 20 feature that appears in hats where the edge of the band is sewn directly to the hat, that is the cracking of the leather where the threads have pierced the same.

A further object is to provide a device 25 whereby the sweat band may be sewn to the hat, the sewing threads of which will pass longitudinally through a leading cord which has been subsequently applied in the well known manner to the edge of the sweat 30 band.

A further object is to provide an attachment whereby the band may be applied to the hat rapidly, accurately and efficiently.

Referring to the drawings wherein I have 35 shown a desired embodiment of my invention,

Figure 1, is a view in side elevation of my improved attachment as used on a sewing machine, the sweat band being shown in 40 cross section and in position to be applied to a hat, the latter of which is partly shown in outline,

Figure 2, is a perspective view of the band 45 guide plate, the band being shown in outline in position thereon,

Figure 3, is an end view of the attachment as seen in Figure 1, and

Figure 4, is an enlarged view of the band 50 as applied to a hat, the binding stitches being clearly shown.

Referring more in detail to the drawing 5 indicates the work support arm and 6 the needle supporting member of a sewing machine of any conventional make. The end 55 of the work supporting arm is provided with the usual shuttle holding head 7.

The head 7 in this instance is provided with two oppositely disposed bosses 9 having bores 10 passing therethrough which are adapted to retain the horizontally disposed 60 arms 11 of a band supporting member, generally indicated by 12. These arms 11 are connected by a vertical inverted V-shaped piece which fixedly carries at the top thereof, a saddle 13. This saddle is provided 65 with a central bore 14 through which loosely passes the pin 15 of a rest 16. The rest is provided on one end with an upturned portion 17 which overlies the edge of the hat band when the latter is in position thereon. 70 The upturned portion is provided with a depending lip 18 which limits the turning movement of the rest 16, the turning thereof providing a yielding movement to the sweat band when the same is being sewn into the 75 hat. The lip 18 contacts with the edge of the saddle 13, when the rest 16 revolves, so that undue rotary movement of the latter is prevented.

The arms 11 are each provided with two 80 adjustable sleeves 19 and 20^A having set screws 21^A therein which hold the sleeves in any position to which they are moved upon the arms 11.

Coiled expansion springs 22^A surround 85 the arms 11 and are disposed between the sleeves 20^A and the end of the bosses 9 and hold the rest 16 in yieldable spaced relation with the head 7. By adjusting the sleeves 19 and 20^A therefore, not only the tension on 90 the support may be adjusted but the distance between the head 7 and the saddle 13 may be varied to accommodate sweat bands of different widths.

The tension of the springs is more or less 95 utilized when a sweat band is placed on the rest 16 and on the head 7 in position to be operated upon, as a slight pressure of the upturned portion 17 against the sweat band will force and hold the same securely against 100 the edge guide 21. This edge guide is a small piece of metal provided with a cut out 22 and a projected portion 23, the latter of which is undercut as at 24 to allow the passage therethrough of the edge of the sweat band and to hold the same down against the plate 27. This guide is suitably fastened as by screws 25 and 26 to the head 7 over the needle hole plate 27, the needle hole 8 being disposed in the cut out portion 22 105 of the guide 21, and adjacent the projected portion 23.

The fastening screw 26 acts as a stop for retainer 28 which is pivoted as at 29 to the edge guide, and is provided with a projecting finger portion 30 which, when the retainer is in place as shown in outline in Figure 2, overlies the sweat band and prevents the same from moving away from the plate 27.

In carrying out the objects of my invention therefore, I have provided the necessary sewing machine attachment and in applying the sweat band to the hat, I provide the sweat band in a well known manner with a leading edge cord 31 which is sewn 15 securely to the edge of the sweat band as by the stitches 32.

Then, instead of sewing the leather sweat band directly to the hat material, as has been done heretofore, I sew the leading cord 20 31 only, to the hat material by the stitches 33 which extend longitudinally of said cord, and do not enter the band at any point.

This removes the objection not only to the ragged appearance of the sewn leather 25 after the hat is used for a time, but also to the bulging effect of the cord produced by stitching the band to the hat directly behind the cord which ultimately causes the latter to curl up and present a rough edge 30 to the head of the wearer.

In this method therefore, of applying the band to the hat, the threads which ordinarily pass through the band and fasten the same to the hat are not used and there is no 35 gradual cutting of the leather by the threads when the hat is being put on, which produces the objectionable ragged edge of leather before referred to.

Having described my invention, what I 40 claim is:—

1. An attachment for sewing machines comprising a guide adapted to be attached to the head piece of the machine, a hat band supporting member held in said head and 45 spring pressed arms on said supporting

member whereby the latter is yieldably maintained in spaced relation with said head.

2. An attachment for sewing machines comprising an adjustable yieldable support, 50 a band guiding member pivotally associated with said support, said guiding member having an overturned portion, and means on said member for limiting the pivotal movement thereof. 55

3. An attachment for a sewing machine having a head portion, comprising a support resiliently held in spaced relation to said portion, a guide plate on the head portion, a hat band supporting member pivotally held in said support, and means on the support whereby the distance between said support and the head portion may be varied, and a retaining finger pivotally associated with the guide plate and adapted to 60 be moved to a position to overlie the hat band beyond said guide plate. 65

4. In combination with a sewing machine having a head portion means resiliently connected to and spaced from said portion for supporting a hat band, a guide on the head for maintaining the edge of the band over the needle hole, and a member pivotally associated with the support for maintaining the edge of the band to be operated upon in 70 position against the guide, said member having an overturned edge portion which overlies said hat band edge. 75

5. In a sewing machine attachment, a guide member against one edge of which 80 contacts a hat band to be operated upon, a retainer pivotally associated with said guide member and having a portion adapted to overlie the band beyond said guide member whereby the same is prevented from moving upwardly above the guide, and means for 85 limiting the pivotal movement of said retainer.

JAMES T. DOWDALL.
